Patented May 21, 1918.

FIG. 1.

FIG. 2.

FIG. 3.

FIG. 5.

UNITED STATES PATENT OFFICE.

WILLIAM KOSTIW, OF BUFFALO, NEW YORK, ASSIGNOR OF ONE-HALF TO HARRY KUDLAK, OF BUFFALO, NEW YORK.

LIFE-SAVING SUIT.

1,267,086.

Specification of Letters Patent. Patented May 21, 1918.

Application filed November 3, 1917. Serial No. 200,079.

To all whom it may concern:

Be it known that I, WILLIAM KOSTIW, a subject of the Emperor of Austria, residing at Buffalo, in the county of Erie and State of New York, have invented certain new and useful Improvements in Life-Saving Suits, of which the following is a specification.

My primary object of the invention is the provision of a suit adapted to be worn for preventing a person from drowning when thrown into the water on such occasions as when shipwrecked at sea, the device being readily inflated during a time of danger.

A further object of the invention is the provision of a life preserver in the form of a bathing suit having inflatable compartments provided with individual deflating means, whereby the degree of inflation may be regulated for each compartment.

20 A still further object of the device is to provide a suit having separate air-tight compartments extending throughout the same, arrangement being made for simultaneously inflating all of the compartments 25 when found desirable, the suit being normally deflated and readily worn by a person, each compartment being separately deflated at will.

In the drawing forming a part of this 30 application and in which like designating characters refer to corresponding parts throughout the several views,

Figure 1 is a front elevation of the device.

35 Fig. 2 is a longitudinal sectional view thereof.

Fig. 3 is a transverse sectional view taken upon line III—III of Fig. 1.

40 Fig. 4 is an enlarged sectional detail view of the communicating and deflating valve arrangement for the compartments.

Fig. 5 is an enlarged longitudinal sectional view of one of the valve members, and

45 Fig. 6 is a transverse sectional view thereof taken on line VI—VI of Fig. 5.

It being designed to provide a garment that will prevent the wearer from drowning, the same may be made in the form of 50 a union or bathing suit 10 having spaced outer and inner walls 11 and 12 respectively and forming an air space therebetween. Encircling partitions 13 are provided between the walls of the suit 10 forming air-tight compartments 14 adapted for

simultaneous inflation by means of a conduit 15 having an inlet pipe 16 and a valved mouth-piece 17 of any desired form.

Cylindrical valve members 18 are arranged in spaced relations within the conduit 14, one of the said valve members being provided for each of the compartments 14, an outlet 19 of the valve member registering with an inlet 20 of the adjacent compartment. A spring pressed valve 21 is 65 provided for each outlet 19, being carried on a stem 22 extending through a bushing 23 in the outer wall 11 of the suit 10 and having a knob 24 upon its outer free end.

The passage of air longitudinally through 70 the valve member 18 is permitted by the provision of ports 25 in its opposite end walls 26. A partition 27 is arranged within the valve member having a normally seated spring pressed valve 28 closing a port there- 75 through, the said valve 28 having a stem 29. It will be understood that the inflation valve 17 may be readily positioned in the mouth of the wearer of the suit 10 and air forced into the conduit 15 by blowing into the 80 same and the air in the conduit will pass longitudinally thereof through the perforations 25 of the valve members 18, the valves 28 being opened by the air pressure but preventing any backward passage of the 85 air through the valve members. When the conduit 15 is filled with air under pressure from the valve 17, the valve 19 of any one or all of the compartments 14 may be manually opened by pulling the knob 24 thereof 90 whereupon air from the conduit 15 will pass through the openings 19 and 20 filling the adjacent compartment. Any back pressure from the compartments 14 to the conduit 15 will only effect to equalize the pressure 95 within the separate compartments, while the pressure of each separate compartment is regulated by means of the valves 19 operated by their respective stems 22. A closure plug 30 is arranged at the bottom 100 of the conduit 15 permitting the escape of any water that may enter the said conduit. It will be seen that a serviceable life preserving suit is arranged which may be readily inflated and the inflation thereof 105 controlled as desired. One or more of the compartments 14 may be permitted to remain deflated if desired while the remainder are fully inflated. In this manner, the suit will accommodate the wearer and only a por- 110

tion such as the upper compartments thereof need be inflated until actual danger is encountered, or even until after the wearer has been thrown into the water.

5. What I claim as new is:—

1. A life saving suit provided with a plurality of encircling compartments, an air conduit communicating with all of said compartments, outlet valves for the compartments within the conduit normally held in closed position, and manually operated normally closed valves between the compartments and said conduit.
2. A life preserving device comprising a union suit having outer and inner walls forming an air space therebetween, spaced partitions between the said outer and inner walls forming compartments, a conduit carried by the outer wall having openings communicating with each of said compartments, an inflating valve at one end of the conduit, a closure plug at the other end of the conduit, a valve member for each compartment arranged within the conduit having a side outlet in one side registering with the opening in the conduit into the adjacent compartment, said valve member also having openings through the opposite ends thereof, a normally closed spring pressed valve for the side outlet of each valve member having a stem projecting outwardly of the outer
10. compartments within the conduit normally held in closed position, and manually operated normally closed valves between the compartments and said conduit.
15. union suit having outer and inner walls forming an air space therebetween, spaced partitions between the said outer and inner walls forming compartments, a conduit carried by the outer wall having openings communicating with the respective compartments, an inflating valve at one end of the conduit, a closure plug at the other end of the conduit, a valve member for each compartment arranged within the conduit having a side outlet in one side registering with the opening in the conduit into the adjacent compartment, said valve member also having openings through the opposite ends thereof, a normally closed spring pressed valve for the side outlet of each valve member having a stem projecting outwardly of the outer
20. compartments within the conduit normally held in closed position, and manually operated normally closed valves between the compartments and said conduit.
25. union suit having outer and inner walls forming an air space therebetween, spaced partitions between the said outer and inner walls forming compartments, a conduit carried by the outer wall having openings communicating with the respective compartments, an inflating valve at one end of the conduit, a closure plug at the other end of the conduit, a valve member for each compartment arranged within the conduit having a side outlet in one side registering with the opening in the conduit into the adjacent compartment, said valve member also having openings through the opposite ends thereof, a normally closed spring pressed valve for the side outlet of each valve member having a stem projecting outwardly of the outer
30. compartments within the conduit normally held in closed position, and manually operated normally closed valves between the compartments and said conduit.

wall of the suit, and having a pull knob on its outer end, and a normally closed valve within each valve member adapted for controlling the passage of air through the con- 35

3. A life preserving device comprising a union suit having outer and inner walls forming an air space therebetween, spaced partitions between the said outer and inner 40 walls forming compartments, a conduit carried by the outer wall having openings communicating with the respective compartments, an inflating valve at one end of the conduit, a closure plug at the other end of the conduit, a valve member for each compartment arranged within the conduit having a side outlet in one side registering with the opening in the conduit into the adjacent compartment, said valve member also having openings through the opposite ends thereof, a normally closed spring pressed valve for the side outlet of each valve member having a stem projecting outwardly of the outer 45 wall of the suit, a transverse partition within each valve member provided with an opening therethrough, and a spring pressed valve for each valve member normally closing the opening through said partition.

In testimony whereof I affix my signature. 50

WILLIAM KOSTIW.
